UNITED STATES PATENT OFFICE.

ALFRED BARKER, OF PHILADELPHIA, PENNSYLVANIA, ASSIGNOR TO JAMES BARKER,
OF PHILADELPHIA, PENNSYLVANIA.

HAIR-DRIER.

1,015,121.

Specification of Letters Patent.

Patented Jan. 16, 1912.

Application filed June 20, 1911. Serial No. 634,239.

To all whom it may concern:

Be it known that I, ALFRED BARKER, a citizen of the United States, residing in Philadelphia, Pennsylvania, have invented 5 certain Improvements in Hair-Driers, of which the following is a specification.

The object of my invention is to provide a hair drier using a fan or other blowing means in which the air as it passes through 10 the apparatus can be thoroughly heated by being deflected so as to pass an electrical heater; this being accomplished in a more thorough manner than heretofore.

The invention also relates to certain details of construction, which will be fully described hereafter; reference being had to the accompanying drawings, in which,—

Figure 1, is a side view of my improved hair drier; Fig. 2, is a longitudinal sectional view, showing the drying chamber and the heating chamber, and Fig. 3, is a transverse sectional view on the line 3—3 Fig. 2.

A is the standard on which is mounted the frame B containing the chamber C. This 25 frame is made in two parts, secured together, as shown. Eccentrically mounted within the chamber is a rotary fan D, mounted on the shaft E of the electric motor F, of any suitable type. This motor is 30 secured to the casing B.

f is the flexible conduit for the electric wires, which connect with any suitable source of power and this conduit has a 35 spring section f' and is hung on a hook a, or other suitable device on the standard A.

G is a casing inclosing the heating medium and this casing is also made in two parts secured together by screws or bolts g, which pass through lugs on each section of 40 the casing and the casing G is secured to the casing B by screws g', which pass through the flanges b on the casing B.

H is a deflecting plate which is of greater diameter than the opening c leading from 45 the casing C. The plate is secured by screws h' to studs h on one half of the casing G. The studs space the deflecting plate a sufficient distance from the opening so as to allow a free passage for the air around the 50 edge of the plate.

Within the chamber formed by the casing G is the frame I consisting of two rings i—i', of metal, or other suitable material, secured to the casing. The outer ring has 55 lugs i'', which are secured to the casing by

screws i''' and the two rings are connected by a wire k. Each of the rings is covered with a non-conducting material and the wire is uncovered. One end of the wire is connected to the terminal k' and the other end of the wire is connected to the terminal k'', as clearly shown in Fig. 3. The outer ring is preferably spaced from the casing, as shown in Fig. 2, and is arranged at a distance from the deflecting plate H so that the air, as it is deflected by the plate, will pass in close contact to the heating wires and will be properly heated before entering the passage g'.

Connected to the casing is a flexible tube 70 N having a nozzle n at its outer end, preferably made of metal and this tube can be adjusted to any position desired by raising and lowering the support M, which consists of a wire bent into shape, as illustrated, and 75 having a head m with a series of teeth which mesh with the teeth on a bracket m' attached to the casing G.

m² is a screw which, when turned, can clamp the support in any position to which 80 it is adjusted.

At one side of the motor F, in the present instance, is a switch P, having a handle p, and the wiring is so arranged that, on turning the handle of the switch in one direction the motor is connected in circuit, driving the fan B, and the electric wire k will also be in circuit and will heat the air as it is driven through the chamber C and the heating chamber. If it is desired to use 85 non-heated air, then the switch is turned in another direction, which cuts out the electric heating wires a and allows the motor to run to drive cool air through the heater. By turning the switch to another position, 90 both the motor and the heating wires are cut out. The switch shown is of the ordinary construction.

The inlet opening c' into the chamber C is preferably provided with a grating, 100 which prevents dust or fine particles of foreign matter from entering the chamber. The fan or blower may be constructed in any manner desired, and the arrangement of the heater may be modified without departing from the essential features of the invention.

I claim:

1. The combination in a hair drier, of a blowing chamber; a blower therein; a heat- 110

ing chamber having an opening communicating with the blowing chamber; an electric heater mounted within the heating chamber; and a deflector also within the 5 heating chamber between the opening from the blowing chamber and the electric heater, said deflector being of greater diameter than the opening, whereby the air is deflected as it passes into the heating chamber, causing 10 it to come in close contact with the electric heater.

2. The combination in a hair drier of a blower casing; a fan therein; means for admitting air to the blower casing and having 15 a passage leading from the casing; an electric motor for driving said fan; a heating chamber connected to the outlet end of the blower chamber; an annular electric heater mounted in said chamber; said heater 20 consisting of inner and outer rings; with electric wires laced on said rings; a deflector within the heating casing; studs carrying said deflector; said deflector being of greater diameter than the opening from the blower 25 chamber whereby the air will be deflected as it is forced through the apparatus and caused to circulate through the heating chamber in contact with the electric wires.

3. The combination in a hair drier of a 30 casing; an inlet and an outlet for the said casing; an electric motor; the shaft of the motor extending into the casing; a fan mounted on the shaft within the casing; a two-part heating chamber transversely ar-

ranged and secured to the outlet end of the 35 blower casing; an annular electric heater secured within the casing; a deflector mounted between the heater and the outlet from the blower chamber so as to deflect the air as it enters the heating chamber; a 40 flexible tube; with means for supporting the tube in any position to which it is adjusted; and an electric switch; with wiring connecting the switch to the motor and to the electric heater.

4. The combination in a hair drier, of a blower casing; a blower therein; means for driving the blower; a heating chamber having an opening forming a communication with the blowing chamber; said heating 50 chamber being of greater diameter than the opening; with a flat electric heater, consisting of inner and outer rings with electric wires laced thereon; and a deflector mounted between the opening leading from the blowing chamber and the electric heater, whereby the air, as it is forced from the blowing casing, will be deflected and will pass in close contact with the wires of the electric heater.

In testimony whereof, I have signed my name to this specification, in the presence of two subscribing witnesses.

ALFRED BARKER.
